UNITED STATES PATENT OFFICE.

ADOLPH H. RIETZEL, OF ATTLEBORO, MASSACHUSETTS, ASSIGNOR TO MORSE ANDREWS COMPANY, OF ATTLEBORO, MASSACHUSETTS, A CORPORATION OF MASSACHUSETTS.

BELT BUCKLE.

Application filed July 1, 1924. Serial No. 723,537.

To all whom it may concern:

Be it known that I, ADOLPH H. RIETZEL, a citizen of the United States, residing at Attleboro, in the county of Bristol and State 5 of Massachusetts, have invented certain new and useful Improvements in Belt Buckles, of which the following is a specification.

This invention relates to that class of buckles which are provided with a pivoting 10 clamping member adapted to engage and bind belts of different thicknesses again the buckle body: and an object of this invention is to provide a clamping member for the buckle, which is formed of a plurality of plates of sheet material, which are connected together in such a manner as to provide a plurality of different belt clamping edges.

A further object of this invention is to form the clamping member of channel bar 20 which provides two spaced apart clamping edges, and to mount a filler member in said channel which provides an intermediate clamping edge.

A still further object of the invention is 25 to mount a separate pivot pin in the space between the side walls of the channel to pivot the clamp in the body of the buckle and to also pivot the bail member in the clamp; these pivoting axes being in different 30 vertical planes.

With these and other objects in view, the invention consists of certain novel features of construction, as will be more fully described, and particularly pointed out in the 35 appended claims.

In the accompanying drawings:

Figure 1 is a plan view of the inner side 40 of a buckle body showing my improved clamping member as pivoted therein.

Figure 2 is an edge elevation of my improved buckle.

Figure 3 is a perspective view showing the channel bar member of the clamp.

Figure 4 shows one of the filler plates 45 which is to be mounted in the channel bar.

Figure 5 shows another of said filler plates which is to be mounted in the channel bar.

Figure 6 shows a perspective view illustrating a pair of pivot pins set end to end.

Figure 7 is an end view showing the two 50 filler plates as mounted in the channel bar, one of the filler plates being of a shape to leave a space for the reception of the pivot pins.

Figure 8 is a side elevation sectioned on line 8—8 of Figure 9, and showing the pivot pins as mounted in the channel bar above one of the filler plates.

Figure 9 shows the laminated clamping plate as mounted in the body of the buckle 60 and a fragment of which is illustrated to show one of its plurality of edges as gripping a thin belt.

Figure 10 shows the clamp bar formed of a single piece of sheet metal folded to form a 65 laminated bar.

Figure 11 shows protuberances formed on some of the plates extending into openings in the other plates to lock the whole together.

It is found in the practical construction 70 and operation of belt buckles of the character in which a plurality of different gripping edges are formed on the clamping member, said edges being of different operating distances from the pivotal center of the 75 clamp, that it is of advantage to set these edges a sufficient distance apart so that a wide variation in the thicknesses of belts may be accommodated and gripped and yet form the clamping member very strong and 80 durable. And the following is a detailed description of the present embodiment of my invention showing one means by which these advantageous results may be accomplished:—

With reference to the drawings, 10 designates the body of a buckle, which may be made in any suitable form, the same being provided with side ears 11 in which the 85 clamping member 12 is pivoted.

It is found in practice that a laminated clamping plate is a very practical construction to be used in this style of buckle, that is the clamping member may be made up of a plurality of plates set side by side and secured together.

To form a clamp of my improved construction, I preferably provide first a channel bar 13 which is U-shaped in cross section one side wall 14 being of a greater 100 length than the other side wall 15, each being provided with a gripping edge to engage and bind a belt against the inner surface of the body of the buckle.

In order to provide an intermediate gripping edge between the side edges, I have provided a pair of filler plates 16 and 17, the plate 16 being substantially the full

depth of the channel bar, while the plate 17 is less than the full depth of this bar, the central meeting edges of these two plates 16 and 17 providing an intermediate belt-grip-
ping edge 18 of a height less than the edge 14 of the channel bar and greater than that of the edge 15 of this bar.

This plate 17 being of less depth than the channel bar provides a space 19 above its upper edge for the reception of the shank portions 20 of the two-part pivot pin 21, also this plate 17 is cut away as at 22 leaving a space for the offset portion 23 of the two-part pivot pin, the ends 24 of this pin member serving to extend beyond the ends of the channel bar to enter openings 25 in the bearing ears 11 of the buckle body to serve as a pivot bearing for the clamping bar. The two part pivot pin constitutes the pivot-pin member.

I have provided a bail member 26 which may be pivotally connected to the clamping bar and to receive which I have slotted as at 27 the back of the channel bar and also 25 that of the filler plates at 27^a and 27^b, through which slots the shank portion of the pivot pins extend.

The bail member 26 is provided with eyes 28 at its inner ends, see Figure 9, through 30 which the inner ends of this divided pivot pin 21 extend and the lower portion of this bail is flattened as at 29 so that when its outer end is raised the portion 29 will engage the edge 30 of the slot 27 to form a 35 stop and so assist in lifting the biting edge of the clamp out of engagement with the belt 31; also when the bail 26 is swung downwardly it is adapted to engage an edge 32 of the slot 27, thereby swinging the clamp- 40 ing bar downwardly into engagement with the belt.

In assembling the parts, it will be noted that the clamping member is laminated or made up of a plurality of plates set side by 45 side and these plates are connected together by pins 33, and the pivot pins 21 are formed of separate pieces of stock and are inserted into the clamping member after the plates have been assembled to serve a double purpose, first, to provide a pin pivoted in the ears 11 on which the clamp is mounted, and second to provide a pivot on which the bail will swing, the axes of both pivots being in different vertical planes. It is to be understood that to form the pivot pin of one piece would require an excessive 55 opening in the bail ends to receive its crank-shaped ends but where made in halves their inner ends may be readily passed through 60 th small bail eye required.

In some instances in providing a laminated channel bar instead of mounting separate filler plates between the side walls of the channel bar, these plates may, in some 65 cases, be formed by folding these walls in-

wardly to provide double walls 37 and 34, if desired, as shown in Figure 10, the wall 34 being preferably shorter than wall 37 to provide an opening 35 for the reception of the pivot pins. In other instances, 70 where the inner plates are formed separately, I may, as shown in Figure 11, form integral protuberances 36 on these plates to fit in corresponding openings in the adjacent walls of the channel bar in place of 75 using through pins 33.

My improved buckle clamp is very strong and durable, is simple and practical in construction and serves to firmly engage and clamp belts of different thicknesses in the 80 body of the buckle.

The foregoing description is directed solely towards the construction illustrated, but I desire it to be understood that I reserve the privilege of resorting to all the 85 mechanical changes to which the device is susceptible, the invention being defined and limited only by the terms of the appended claims.

I claim:

1. A buckle comprising a body portion, a clamping member pivoted in said body, and formed of a sheet metal channel bar having side walls providing two spaced apart clamping edges, a bail member, a pivot for 95 said bail in the channel of said bar, and a filler member also in said channel providing an intermediate clamping edge, all of said edges being located different effective operating distances from the pivotal point. 100

2. A buckle comprising a body portion, a clamping member for engaging and binding the belt therein, a bail member, and an independent pivot pin member mounted in 105 said clamp to serve as a pivot for said bail and having offset end portions on which said clamp is mounted in the buckle body.

3. A buckle comprising a body portion, a clamping member formed of a channel bar, a bail member, and a separate pivot pin member having a portion fitted into a space between the side walls of said channel bar to provide a pivot for the bail, and having its end portions offset to provide pivots on 110 which said clamping member is mounted in said body.

4. A buckle comprising a body portion, a clamping member formed of a channel bar, a bail member, and a separate pivot pin member having a portion fitted into a space 115 between the side walls of said channel bar to provide a pivot for the bail and having its end portion mounted in said body to provide a pivot for said clamping member, the axes of said clamping member pivot and bail being in different vertical planes. 120

5. A buckle comprising a body portion, a clamping member formed of a plurality of plates set side by side and providing a plurality of clamping edges, each located a dif- 130

- ferent distance from the pivotal point, a bail member, and a pair of separate pivot pins forming the pivot pin member secured to said plates, each having a portion on 5 which the bail is pivoted and a portion pivoted in said body portion.
6. A buckle comprising a body portion, a clamping member formed of a plurality of plates set side by side and providing a plurality of clamping edges, each located a different distance from the pivotal point, a bail member, a pair of separate pivot pins forming the pivot pin member secured to said plates, each having a portion on which the 10 bail is pivoted and a portion pivoted in said body portion, the axes of the pivot in said body portion and bail pivot being in different vertical planes.

7. A buckle comprising a body portion, a clamping member formed of a plurality of 20 layers or thicknesses of stock having a plurality of gripping edges and spaced recesses in its opposite edge, said member being pivoted in said body, and a bail member having its ends pivoted in said recesses of 25 said member and on an axis different from that on which said member is pivoted.

8. A buckle comprising a body portion, a clamping member formed of a channel bar, 30 filler plates having gripping edge portions, said plates being located between the walls of said bar and formed integral therewith, and a bail member pivoted in said clamp.

In testimony whereof I affix my signature.

ADOLPH H. RIETZEL.
